UNITED STATES PATENT OFFICE

DONALD W. MERSEREAU, OF ROCHESTER, NEW YORK, ASSIGNOR TO GENERAL RAILWAY SIGNAL COMPANY, OF ROCHESTER, NEW YORK

TRAP CIRCUIT FOR RAILWAY SIGNALING SYSTEMS

Application filed March 12, 1931. Serial No. 521,905.

This invention relates to a trap circuit for railway signaling systems, and more particularly to a trap circuit which is applicable to a comparatively short track section.

A trap circuit in railway signal parlance is an arrangement of track circuits and associated relays whereby the presence of a train in a particular section may be signified, even though a part of said section, of a length greater than the shortest train used, cannot be track-circuited for local reasons, as, for instance, where there are one or more railroad crossings crossing such sections and prohibit track circuiting. In other words, a trap circuit is an arrangement of devices whereby section occupancy is indicated by the entrance of a train into such section, and clearing of such section is indicated by the departure of such train, even though this train may occupy a non-track-circuited portion of such section for a time and during such occupancy this occupancy is indicated because the train has not yet departed. The particular embodiment of the invention illustrated is particularly applicable to a single track railroad, where a train may move in both directions, and wherein the signals for governing the movement of trains into a particular section are preferably manually controlled and are preferably interlocked in such a way that only one of these starting signals may be cleared at a time.

More specifically it is proposed in accordance with the present invention to employ a track circuit in the section under consideration on each side of an intermediate non-track circuitable portion, and to provide two stick relays for each of said track circuits, one of these stick relays being governed by the entrance of a train into said track section and the other stick relay being deenergized upon the entrance of a train into that section, together with circuits and devices for restoring both of these stick relays only in the event that a train has departed from the other end of said section with the track circuit at the entering end unoccupied.

Other objects, purposes and characteristic features of the present invention will in part be pointed out hereinafter and will in part

be obvious from the accompanying drawing.

In describing the invention in detail reference will be made to the accompanying drawing which illustrates one particular embodiment of the present invention.

Referring to the drawing, the track rails 4 have been shown divided into blocks by insulating joints 5, of which the block O and the adjacent ends of the blocks N and P only have been illustrated, of which the block O is still further divided into track circuit sections by insulating joints 6. As shown in the drawing the west end of the block O is provided with a track circuit including the track battery 22 and the track relay 22T, whereas the east end of the block O is track circuited by a track battery 23 and a track relay 23T, whereas the intermediate section of the block O is left non-track-circuited by reason of the presence of the cross tracks "Track 1", "Track 2" and "Track 3" shown. In this connection, it is of course understood that the invention may be applied to other signaling problems, as, for instance, where a cross-over between two parallel railway tracks is employed, and where such cross over may have rusty rails prohibiting the use of the usual track circuit protection, or the invention may be applied under other circumstances where it is impossible to manifest the presence of a short train, such as a gasoline motor car or for other reasons such as dirty rails.

As illustrated, the starting signal 12 is employed to govern the movement of east bound trains into the single track section, whereas the leaving signal 14 is used to govern the movement of east bound trains out of the block O, and the starting signal 13 is employed to govern the movement of west bound trains into the block O, whereas the leaving signal 11 is employed to govern the movement of west bound trains out of the block O. The signals 11 and 14 are controlled in accordance with traffic conditions in advance thereof in the usual manner.

It is believed expedient to first trace all of the normally closed circuits, as illustrated in the drawing, and thereafter consider the functioning of the various relays in response to the movement of a train through the block O.

Under normal conditions, as illustrated in the drawing, a stick relay 22L is energized through both of the following circuits:—(1) beginning at the terminal (+) of a suitable battery, front contact 16 of the relay 23TP, wire 17, front contact 18 of the relay 22TP, wires 19, 20 and 21, winding of the relay 22L, wire 24, contact 25 of the signal 12 closed only when this signal assumes the stop position, wire 26 to the other terminal (−) of said battery, and (2) beginning at the terminal (+) of said battery, stick contact 27 of the relay 22L, wires 28 and 21, winding of the relay 22L, wire 24, contact 25 of signal 12, and wire 26 back to the other terminal (−).

The stick relay 22TP is normally energized through both of the following circuits:—(1) beginning at the terminal (+) of a suitable battery, front contact 30 of the relay 22L, wires 31 and 32, winding of the relay 22TR, wire 33, front contact 34 of the track relay 22T to the other terminal (−) of said battery, and (2) beginning at the terminal (+) of the same battery, stick contact 35 of the relay 22TP, wires 36 and 32, winding of the relay 22TP, wire 33, front contact 34 of the track relay 22T to the other terminal (−).

Similarly, the relay 23L is normally energized through each of the following circuits:—(1) beginning at the terminal (+) of a suitable battery, front contact 46 of the relay 22TP, wire 47, front contact 48 of the relay 23TP, wires 49, 50 and 51, winding of the relay 23L, wire 54, contact 55 of the signal 13 closed only when this signal assumes the stop position, wire 56, to the other terminal (−) of said battery, and (2) beginning at the terminal (+) of said battery, stick contact 57 of the relay 23L, wires 58 and 51, winding of the relay 23L, wires 54, contact 55 of signal 13, wire 56, to the other terminal (−). Also, the relay 23TP is normally energized through both of the following circuits:—(1) beginning at the terminal (+) of a suitable battery, front contact 60 of the relay 23L, wires 61 and 62, winding of the relay 23TP, wire 63, front contact 64 of the track relay 23T, to the other terminal (−) of said battery, and (2) beginning at the terminal (+) of the same battery, stick contact 65 of the relay 23TP, wires 66 and 62, winding of the relay 23TP, wire 63, front contact 64 of the track relay 23T, to the other terminal (−) of said battery.

It is readily apparent that the track repeater relay TPO for the entire block O is energized only in the event that both of the repeater track relays 22TP and 23TP are energized, namely through the following circuit:—beginning at the terminal (+) of a suitable battery, front contact 70 of the relay 22TP, wire 71, front contact 72 of the relay 23TP, wire 73, winding of the relay TPO to the other terminal (−).

Although the starting signals 12 and 13 are

not necessarily manually controlled, but are preferably interlocked so that only one of these signals can clear at a time, these signals 12 and 13 have been shown manually controlled by the polar control relay CR, which control relay is preferably controllable from a central office or dispatcher's office DO, as illustrated by the line wire 75 and the lever L located in this central office DO, from which it is apparent that movement of the lever L to the right will energize the control relay CR to the right, this by reason of the flow of current of positive polarity, and movement of the lever L to the left will energize the control relay CR to the left, as through the medium of current of negative polarity. The clearing of these starting signals 12 and 13, is of course, also dependent on traffic conditions, not only of the block O but also of the block next in advance of said block O for the particular signal. In other words, the clearing of the signal 12 depends upon traffic conditions in advance of the signal 14, and the clearing of the signal 13 depends on traffic conditions in advance of the signal 11, and although this may be accomplished in any one of many different ways, it has been shown accomplished through the medium of signal contacts 77 and 78 associated respectively with the signals 11 and 14.

Operation

For the purpose of explanation, let us assume that there is an east bound train moving in the single track section N, and that the operator at the central office DO clears the signal 12 to allow this train to pass through the single track section O. This clearing of the signal 12 will be accomplished by movement of the lever L to the right hand position, signifying east bound traffic and resulting in the energization of the control relay CR to the right, in which condition the signal 12 may clear through the following circuit:—beginning at the terminal (+) of a suitable battery, contact 78 of the signal 14 closed only when this signal 14 assumes either the clear or caution position, wire 80, front contact 81 of the relay TPO, wire 82, polar contact 83 of the relay CR, wire 84, mechanism of the signal 12, to the other terminals of said battery. Clearing of the signal 12 opens the contact 25 so that the stick relay 22L is deenergized.

It is desired to point out at this juncture that if the operator in the central office DO in the meantime has changed his mind and wishes to put the signal 12 back to the stop position, this return of the signal 12 to the stop position will effect reenergization of the stick relay 22L, this because the pick-up circuit for said stick relay 22L and including the contacts 18 and 16, respectively, of the relays 22TP and 23TP is closed. Attention is also directed to the fact that even though the stick

relay 22L has by its dropping opened its contact 30, that the relay 22L is not de-energized, because the second circuit for this relay 22TP which includes the contacts 34 and 35 is still intact.

5 Proceeding, on the assumption that the operator leaves the signal 12 in the clear position, let us now observe the effect of the entrance of an east bound train into the block O. The entrance of the east bound train under consideration into the block O effects deenergization of the track relay 22T, thereby deenergizing the relay 22TP, and deenergization of the relay 22TP by the opening of its contact 70 effects deenergization of the repeater relay TPO for the block O.

10 If we assume that the east bound train under consideration is so short that the track relays 22T and 23T are both energized while this train is occupying the un-track-circuited portion of the block O, then even under this consideration, namely, with the track relays 22T and 23T energized, the relay TPO remains deenergized, this because one pick-up 15 circuit for the stick relay 22L is open at the contact 18 of the relay 22TP, and the other pick-up circuit for the relay 22L is open at the back contact 16 of the relay 23TP. Also, the pick-up circuit for the relay 22TP is open 20 at the back contact 30 of the relay 22L, so that both of these relays 22L and 22TP will remain deenergized.

25 Let us now assume that the short train under consideration continues its movement in an easterly direction and treads upon the track circuit containing the track relay 23T. It is of course understood that since the relay TPO is now deenergized that the signal 12 has again been operated to its stop position.

30 With the track relay 23T now deenergized, the following pick-up circuit for the relay 22L is closed:—beginning at the terminal (+), back contact 16 of the relay 23TP, wires 86, 20 and 21, winding of the relay 22L, wire 45 24, contact 25 of the signal 12, wire 26 to the other terminal (—). With the relay 22L now energized it will be stuck up through its stick contact 27 and remain energized irrespective of the opening of the back contact 16 of the relay 23TP.

40 Also, closing of the contact 30 of the relay 22L will effect reenergization of the stick relay 22TP, this because the contact 34 of the track relay 22 has been reclosed. Attention is directed to the fact that the east bound train by its deenergization of the track relay 23T did not effect deenergization of the stick relay 23L but merely effect deenergization of the repeater track relay 23TP. It is thus apparent 45

50 that the relay TPO remains deenergized until the departing train has left the track circuit containing track relay 23T, and when this occurs the track relay 23T is reenergized and effects reenergization of the relay 23TP, through the medium of the front contact 72

55 of which the relay TPO is energized as soon as the east bound train under consideration has left the block O.

60 It is thus apparent that the relay TPO does not only indicate occupancy of one or the other or both of the track circuits included in the block O, but also indicates whether a train which entered one end of the block O has departed from the other end of this block. Furthermore, the function of definitely indicating the occupancy of a particular block in 65 spite of the presence of a non-track-circutitable section in such block these functions are carried out without the provision of additional insulating joints or other means for indicating the departure of a train, that is, only two insulated track sections, one on each 70 side of the non-track-circutitable section, are required. It is of course understood that since the apparatus shown at the east end is 75 identical to the apparatus shown at the west end of the block O, that a west bound train will be manifested during its occupancy of the block in exactly the same way as already explained in connection with the movement 80 of an east bound train, and for this reason certain like parts at the east end of the block O have been designated by corresponding 85 reference characters with an exponent one.

90 It should be understood that the trap circuit under consideration may be used for indicating occupancy of a particular track section at other locations, such as at cross-overs, and that this same means may be employed for effecting approach locking in connection with switch machines for controlling the 95 points of such cross-overs, and that the invention may be applied to other types of railway signaling systems than the particular one illustrated, in the same way as ordinary 100 track relays are employed in other signaling systems, all without departing from the spirit or scope of the present invention. Also, it is desired to be understood that the particular embodiment of the invention illustrated has 105 not been selected for the purpose of showing the precise manner in which the invention must be applied nor has it been selected for the purpose of showing the scope of the invention, and it is further desired to be understood 110 that various changes, modifications and additions may be made to adapt the invention to the particular problem encountered in practicing the same, all without departing from the spirit or scope of the invention 115 or the idea of means underlying the same, except as demanded by the scope of the following claims.

120 What I claim as new is:—

1. A trap circuit for a track section of a 125 railway signaling system in which there is an intermediate portion which can not be track-circuited comprising, a normally closed track circuit including a track relay for each of the two end portions of said section, a 130

stick relay for each of said end portions, and means including said track relays for dropping one of said stick relays upon the entrance of a train into one end of said section and for picking up such stick relay upon departure of a train from the other end of said section.

2. A trap circuit for a track section of a railway signaling system in which there is an intermediate portion which can not be track-circuited comprising, a normally closed track circuit including a track relay for each of the two end portions of said section, a stick relay for each of said end portions, means including said track relays for dropping one of said stick relays upon the entrance of a train into one end of said section and for picking up such stick relay upon departure of a train from the other end of said section, and a repeater relay energized only if both of said stick relays are energized.

3. A trap circuit for a track section of a railway signaling system in which there is an intermediate portion which can not be track-circuited comprising, a normally closed track circuit including a track relay for each of the two end portions of said section, two stick relays for each of said end portions the second stick relay of which can be picked up only if the first of said stick relays is energized and the associated track relay is energized and will remain stuck up so long as said track relay is energized, and means for picking up the first of said stick relays upon departure of a train from the other end of said section.

4. A trap circuit for a track section of a railway signaling system in which there is an intermediate portion which can not be track-circuited comprising, a normally closed track circuit including a track relay for each of the two end portions of said section, two stick relays for each of said end portions the second stick relay of which can be picked up only if the first of said stick relays is energized and the associated track relay is energized and will remain stuck up so long as said track relay is energized, means for picking up the first of said stick relays upon departure of a train from the other end of said section, and a repeater relay energized only if said two second stick relays are energized.

5. In a trap circuit for railway signaling systems, the combination with a section of track having a portion which cannot be track-circuited, an insulated track-circuited section on each side of said portion each of which includes a normally energized track relay, a stick relay associated with each of said track relays, and means including said track relays for dropping the stick relay at one end if a train enters that end of said section of track and for again picking up said stick relay

when said train departs from the other end of said section of track.

6. In a trap circuit for railway signaling systems, the combination with a section of track having a portion which cannot be track-circuited, an insulated track-circuited section on each side of said portion each of which includes a normally energized track relay, a stick relay associated with each of said track relays, and means including said track relays for dropping the stick relay at one end if a train enters that end of said section of track and for again picking up said stick relay when a train departs from the other end of said section of track with said one end of said section unoccupied.

7. In a trap circuit for railway signaling systems, the combination with a section of track having a portion which cannot be track-circuited, an insulated track-circuited section on each side of said portion each of which includes a normally energized track relay, a stick relay associated with each of said track relays, and means including said track relays for dropping the stick relay at one end if a train enters that end of said section of track and for again picking up said stick relay when a train departs from the other end of said section of track with said one end of said section unoccupied, and another relay energized only if both of said stick relays are energized.

8. In a trap circuit for railway signaling systems, the combination with a section of track having a portion which cannot be track-circuited, an insulated track-circuited section on each side of said portion each of which includes a normally energized track relay, a signal governing the entrance of trains into one end of said section of track, a first stick relay energized only if said signal is at stop, a second stick relay energized only if the track relay at said one end is energized and which can be picked up only if said first stick relay is energized, and means for picking up said stick relays upon deenergization of said other track relay.

9. In a trap circuit for railway signaling systems, the combination with a section of track having a portion which cannot be track-circuited, an insulated track-circuited section on each side of said portion each of which includes a normally energized track relay, a signal governing the entrance of trains into one end of said section of track, a first stick relay energized only if said signal is at stop, a second stick relay energized only if the track relay at said one end is energized and which can be picked up only if said first stick relay is energized, and means for picking up said stick relays upon deenergization of said other track relay providing said one track relay is then energized.

10. A trap circuit for railway signaling systems comprising; a block including a

- track-circuited section including one track relay, an intermediate non-track-circuited section and a track-circuited section including another track relay; a block relay; and means for deenergizing said block relay effective upon deenergization of said one track relay, and effective to reenergize said block relay upon deenergization followed by reenergization of said another track relay.
- 5 11. A trap circuit for railway signaling systems comprising; a block including a track-circuited section including one track relay, an intermediate non-track-circuited section and a track-circuited section including another track relay; a block relay; and means for deenergizing said block relay effective upon deenergization of said one track relay, and effective to reenergize said block relay upon deenergization followed by reenergization of said another track relay providing said one track relay has been reenergized in the meantime.
- 10 12. A trap circuit for railway signaling systems comprising; a block including a track-circuited section including one track relay, an intermediate non-track-circuited section and a track-circuited section including another track relay; a block relay; and means for deenergizing said block relay effective upon deenergization of said one track relay, and effective to reenergize said block relay upon deenergization followed by reenergization of said another track relay providing said one track relay has been reenergized in the meantime.
- 15 13. A trap circuit for railway signaling systems comprising; a block including a track-circuited section including one track relay, an intermediate non-track-circuited section and a track-circuited section including another track relay; a block relay; and means for deenergizing said block relay effective upon deenergization of said one track relay, and effective to reenergize said block relay upon deenergization followed by reenergization of said another track relay providing said one track relay has been reenergized in the meantime.
- 20 14. A trap circuit for railway signaling systems comprising; a block including a track-circuited section including one track relay, an intermediate non-track-circuited section and a track-circuited section including another track relay; a block relay; and means for deenergizing said block relay effective upon deenergization of said one track relay, and effective to reenergize said block relay upon deenergization followed by reenergization of said another track relay providing said one track relay has been reenergized in the meantime.

In testimony whereof I affix my signature.
DONALD W. MERSEREAU.
